UNITED STATES PATENT OFFICE.

ALFRED STELL, OF STEETON, NEAR KEIGHLEY, AND JOHN STELL AND HENRY WELCH,
OF KEIGHLEY, ENGLAND; SAID WELCH ASSIGNOR TO SAID ALFRED STELL AND
SAID JOHN STELL.

SPINNING-MACHINE.

1,124,672.

Specification of Letters Patent.

Patented Jan. 12, 1915.

Application filed February 5, 1914. Serial No. 816,758.

To all whom it may concern:

Be it known that we, ALFRED STELL, JOHN STELL, and HENRY WELCH, subjects of the King of Great Britain, and residents, respectively, of Greenhill, Steeton, near Keighley, in the county of York, England, 30 Devonshire street, Keighley, aforesaid, and 25 Rylstone street, Keighley, aforesaid, have invented a certain new and useful Improvement 10 in Spinning-Machines, of which the following description, together with the accompanying sheets of drawings, is a specification.

It relates to doffing mechanism for machines of the class well known as cap spinning, doubling, twisting and like frames, which are used in the production of yarns or threads of fibrous substances.

Our said doffing mechanism is used for 20 simultaneously effecting the removal of all the full bobbins from their spindles and then for placing thereon empty bobbins with the yarns or threads so secured that the spinning or like operations may be re-started.

Our present invention consists in the application of improved parts to the type or class of mechanism described in the United States Patent specification No. 995565, such 30 application of improved parts having for its object the carrying out with greater efficiency the process of removing the full bobbins and substituting empty bobbins in their place. The devices which we employ are illustrated in the accompanying sheets of drawings wherein:—

Figure 1 is an end elevation of a sufficient portion of a spinning frame to illustrate the application thereto of our improvements. Fig. 2 is a front elevation of parts shown by Fig. 1. Fig. 3 is a sectional end elevation of a portion of a spinning frame having our improvements applied thereto, the different parts thereof being shown in the positions they occupy during the spinning operations. Fig. 4 is a similar view to Fig. 3 and shows the parts in position after the first part of the doffing operations has been performed, that is, when the "caps" have been raised by the spindles and returned by their holders. Fig. 5 is also a similar view to Fig. 3 and illustrates the positions which the several parts occupy when the spindles have been lowered clear of the "caps" with the caps drawn away, the full bobbins held upon their spindles and the parts for the reception

of the full bobbins ready to be placed into position to receive them. Fig. 6 is also a sectional end elevation and shows the parts in their positions when the full bobbins have been removed and the empty bobbins have 60 been adjusted in position for being lowered upon the spindles. Fig. 7 is a front elevation of a device for receiving and moving the full and empty bobbins. Fig. 8 is a plan thereof. Fig. 9 is a view as seen in the direction at right angles to Fig. 7.

A indicates the end frame of the machine B, B' the upper and lower fixed rails of the machine, and C, C' the front rollers thereof.

The spindle rail 1 is mounted upon the 70 vertical racks 2 which pass through and are guided by the fixed rail B'. The said rail 1 supports the spindles 3 upon which are mounted the caps 4. Whirls 5 rotate the bobbins 6 which take over tubes 7 in the 75 usual manner. The racks 2 are raised and lowered by means of the pinions 9 which are fixed upon the shaft 9 the latter being carried in bearings 10 supported by the rail B'. The shaft 9 is rotated by the hand wheel 11 80 through the gear wheels 12 and 13 in manner well known.

Carried by the bearings 10 is another shaft 14 (operated by a handle 14a) upon which are fixed gear wheels 15 meshing with racks 85 16, said racks carrying at their upper ends brackets 17. Mounted upon said brackets 17 is a shaft 18 which is operated by a handle 20; said shaft 18 has mounted upon it pinions 19 which gear with racks 21 moving in 90 the brackets 17. The racks 21 support a bar 22 upon which are mounted brackets 23 such brackets supporting the shaft 24, lever arms 25 on which carry the bar 26, this latter acting as a thread-holding device in manner 95 hereinafter described.

Supported by the bracket 23 and in proximity to the bar 22 is another bar 27 which has mounted upon it racks 28, these latter gearing with pinions 29 which are free to rotate upon studs 30 mounted upon the plate 22. The pinions 29 support plates 31 upon which are mounted the semi-circular supporting tubes or "half tubes" 32, 33, which are approximately of the same diameter as 100 the interior of a bobbin 6. These supporting tubes have to be placed in contact with the spindles 3 in the manner hereinafter described, and in order to enable them to accommodate themselves to slight irregulari- 110

- 2
- ties in the sizes or positions of said spindles we arrange springs 34, 35, to intervene between the plate 36, which is fixed to the pinion 29, and the downwardly extending parts 37, 38 of the plate 31.
- 8   Mounted in bearings 39 are racks 40 which are reciprocated by toothed quadrants 41, fixed upon the shaft 42, these being operated by the handle 43 in manner well known.
- 10   The racks 40 carry a plate 42^a upon which are mounted a series of bifurcated holders 43^a which are for the purpose of laying hold of and moving the caps 4 in manner well understood.
- 15   In brackets 44 carried by the plate 42^a (or in fixed bearings or bearings which will allow vertical movement) is a shaft 45 upon which are mounted spring arms 46 having their ends 47 turned at an angle and if desired having their points sharpened. This shaft 45 is oscillated by the handle 48 and is for the purpose of taking beneath the full bobbins 6 or empty bobbins 6^a somewhat in the manner as shown by Fig. 5, or the points 25 of the ends 47 may be pressed or dug into the yarn on the bobbins.
- To carry out the process of "doffing" the operations of our improved apparatus are as follows:—The caps 4 are raised by means 30 of the spindle rail 1 into the position indicated by Fig. 4, after which the plate 42^a with the bifurcated supporting pieces 43^a is advanced so that the pieces 43^a pass beneath the flanges 4^b on the caps 4 in order 35 to support said caps. The spindle rail 1 is then lowered to carry the spindles clear of the lower ends of the caps 4. The brackets 17 carrying the bar 22 upon which are mounted the plates 31 are then raised and 40 the racks 21 advanced so as to carry the bifurcated ends of the plates 31 beneath the bottom flanges of the bobbins 6 so that they thus support said bobbins. The racks 40 are then returned to their former positions so 45 as to carry the caps away from the spindles and in proximity to the rail B as shown by Fig. 5. The brackets 17 and consequently the plates 31 are then raised so as to carry the bobbins 6 sufficiently above the ends 47 50 of the arms 46 in order to permit these to be moved beneath said bobbins 6 as shown by Fig. 5. The plates 31 are then moved from beneath said bobbins' flanges the bobbins being then supported by the arms 46.
- 55   After this the plates 31 are slightly lowered and advanced so that the half tubes 32 or 33 take against the spindles 3 somewhat as shown by Fig. 8. The bobbins 6 are then released by the movements of the arms 46, hence said bobbins descend upon the half tubes 32. The plates 31 are then raised until they are clear of the upper ends of the spindles 3 so that the plates 31 may be rotated by their pinions 29 to cause the full 60 bobbins 6 to be moved away from the spindles 3 and the empty bobbins which are supported by the half tubes 33 to be carried vertically over said spindles. See Fig. 6. The plates 31 are then lowered so as to move the empty bobbins somewhat into the position in which the full bobbin 6 is shown in Fig. 5, and the arms 46 moved so as to support same. The plates 31 are now to be lowered to a position where the half tubes 33 are clear of the lower ends of the bobbins 6^a, 75 on which said plates 31 are moved horizontally away from the spindles 3, so that the arms 46 may be moved to release the empty bobbin 6^a which then fall over or upon the tubes 7. The caps 4 are advanced to a position vertically over the spindles 3 which are then raised so as to carry the empty bobbins within them as well as to support said caps, after which the bifurcated holders 43^a are returned to the position indicated by 80 Fig. 3, and the spindle rail moved into the spinning position. The notched rod 26 is then moved by its arms so as to pass over the upper ends of the pull bobbins on the half tubes 32 this movement causing the 90 threads to be placed in proximity to the notched plate 5^a on the upper end of the whirl 5 so that on the tubes 7 being restarted into action the threads are caught in the serrations in said flange 5^a whereby such 95 threads are placed in their desired positions for the commencement of the winding on the new set of empty bobbins, the threads extending from the full bobbins being broken by being held by the notched bar or 100 rod 26.
- Such being the nature and object of our invention what we claim is:—
1. In doffing mechanism for spinning machines of the class described, means for operating the spindles in a vertical direction, devices for removing the caps from said spindles means for supporting the bobbins during the descent of the spindles and tubes, instruments made to engage the spindles and enter the axial openings in said bobbins prior to the withdrawal therefrom of their spindles and means for operating said instruments.
  2. In doffing mechanism for spinning machines of the class described, means for operating the spindle in a vertical direction, devices for removing the caps from said spindles, means for supporting the bobbins during the descent of the spindles and tubes, half tube devices and means for presenting said half tube devices for contact with their spindles so that on the further descent of the spindles and tubes the bobbins will be received by said half tubes and means for operating said half tubes so that the one series which receives the full bobbins may carry same out of alinement with their spindles and simultaneously bring the empty bobbins into such alinement as herein specified.

3. In doffing mechanism for spinning machines of the class described, means for operating the spindles in a vertical direction, devices for removing the caps from said spindles, means for supporting the bobbins during the descent of the spindles and tubes, half tube devices mounted upon rotary parts, means for actuating said rotary parts so that at one time one series of half tubes may 10 be in close proximity with the spindles and at another time the other series of half tubes may be in close proximity.
4. In doffing mechanism for spinning machines of the class described, means for operating the spindles in a vertical direction, devices for removing the caps from said spindles, means for supporting the bobbins during the descent of the spindles and tubes, half tube devices mounted upon rotary parts, 15 and adapted to receive the bobbins upon the descent of the spindles, rack and pinion devices for actuating said rotary parts and means whereby said rack and pinion devices may be operated to move the parts into the 20 desired positions.
5. In doffing mechanism for spinning machines of the class described, means for operating the spindles in a vertical direction, devices for removing the caps from said spindles, means for supporting the bobbins during the descent of the spindles and tubes, half tube devices, means for actuating same 25 so that one series at one time are in position for receiving the full bobbins, while at another time the other series are in position for depositing the empty bobbins, means whereby said devices may be raised and lowered or adjusted in suitable positions horizontally to meet the requirements desired.
- 40 6. In doffing mechanism for spinning and like machines devices for removing the caps from the spindles in said machines means for raising and lowering the spindles which support the caps and means for supporting the bobbins during the time that the spindles and the tubes upon which the bobbins are mounted are descending below the certain position, and half tube devices for taking into the spaces or openings in the bobbins during the time that the spindles are 45 also within said bobbins so that on the withdrawal of said spindles said half tube devices will retain said bobbins.
7. In doffing mechanism for spinning and like machines of the class described, half tube devices for receiving the full bobbins from the spindles in said spinning machines and for placing the empty bobbins into alinement therewith, and resilient bearings for supporting said half tube devices so that the 50 same may be yieldingly pressed against said spindles for the purpose herein stated.
8. In doffing mechanism for spinning and like machines devices for removing the caps from the spindles in said machines means 55 for removing the full bobbins from said spindles, means for placing empty bobbins on said spindles, mechanism for rotating the bobbin remover and bobbin replacer to cause them to selectively coöperate with the spindles, and a notched bar for holding the threads or yarns extending from the full bobbins after they have been doffed or removed.
- In testimony whereof we have signed our 70 names to this specification in the presence of two subscribing witnesses.
